M. T. KEARNS.
GLOVE DRIER FORM.
APPLICATION FILED FEB. 11, 1920.

1,369,341.

Patented Feb. 22, 1921.

UNITED STATES PATENT OFFICE.

MARGARET T. KEARNS, OF NEWARK, NEW JERSEY.

GLOVE-DRIER FORM.

1,369,341.

Specification of Letters Patent. Patented Feb. 22, 1921.

Application filed February 11, 1920. Serial No. 357,978.

To all whom it may concern:

Be it known that I, MARGARET T. KEARNS, citizen of the United States, residing at Newark, in the county of Essex and State 5 of New Jersey, have invented certain new and useful Improvements in Glove-Drier Forms, of which the following is a specification.

This invention relates to a glove drier 10 form and particularly to a construction wherein the body or palm portion is adapted to rigidly support interchangeable digital members to permit the rearrangement thereof upon said body.

15 The invention has for an object to provide a novel and improved construction of body portion having sockets at its upper edge adapted to receive and rigidly support shanks from coöperating digital members 20 and also having sockets at its opposite side edges to similarly support thumb members.

A further object of the invention is to 25 present a novel construction of digital member having a shank adapted to be secured against movement in a kerf formed in a body portion, said member being provided with a portion beyond said shank to inclose the upper edge of said kerf.

Other and further objects and advantages of the invention will be hereinafter set forth and the novel features thereof defined by the appended claims.

In the drawing—

Figure 1 is an elevation of the invention; 35 Fig. 2 a vertical section on line 2—2 of Fig. 1;

Fig. 3 is a top plan of the body portion;

Fig. 4 is a side elevation thereof;

Fig. 5 is a detail perspective of one of 40 the digital members, and Fig. 6 is a detail of a modified form of socket.

Like numerals refer to like parts in the several figures of the drawing.

The numeral 10 designates the body or 45 palm portion which may be formed of any desired material or configuration, and is herein shown with the wrist or base portion 11 substantially oval in cross section while the upper part 12 thereof is flattened into 50 an elongated oval, as shown in Fig. 3. This part 12 is formed with a series of transverse kerfs or channels 13 to form sockets therein adapted to receive the shanks 14 carried by the digital or finger members 15. These sockets 55 are formed with a straight or plane bottom wall 16 which contacts with a similar

wall 17 on the shanks 14 and presents lateral movement of the digital members when the parts are secured together. This securing may be effected by any desired means, for 60 instance a cross pin 18 extending through an aperture 19 longitudinally of the body portion and also through apertures 20 in the digital members. This provides means by which the digital members may be inter- 65 changeably mounted upon the body portion, as by withdrawing the pin they may be arranged for either a right or left hand glove.

The digital or finger members 15 are shaped to conform to the fingers of a hand 70 or glove and at their base 21 are extended beyond the angular shank portion 14 to completely cover the upper edge of the socket at the finger base and protect the same against moisture, as shown in Fig. 2. The finger 75 members are preferably spaced apart so as to permit access between the same for cleaning purposes when the glove is in position thereon.

In fitting a glove upon the form, particularly when the glove is wet, it is desirable to 80 remove the thumb of the form so that the glove fingers may be worked straight downward thereon. For this purpose the thumb member 22 is provided with a reduced shank 85 23, similar to the finger members, which enters a diagonally disposed socket 24 upon the side of the form body. This shank is removably secured in the socket by a pin 25 entering an aperture 26 in the body and 90 passing the shank 23. The thumb member is also provided at one side of its base with a shoulder 27 by which it is positioned at the proper angle from the body to be separated therefrom for drying purposes. The 95 sockets 24 are duplicated at the opposite sides of the form so that the thumb portion may be interchanged for either right or left hand gloves when the finger members are rearranged for that purpose. The disposition of the thumb member at the side of the body locates the thumb in substantially the vertical plane of the fingers and thus presents a flat front and back surface for unobstructed cleaning of a glove. While this 100 form may be constructed of any desired material it is particularly adapted for production from wood as the sockets may be conveniently formed therein.

The sockets have been described as 110 straight slots but they may be otherwise formed, for instance the body or hand por-

tion 30 may have formed therein dovetail sockets 31 adapted to receive the finger member 32 having a dovetail shank 33 to fit the socket, as shown by the modified form 5 of the invention in Fig. 6.

In the use of the form the digital members may be interchangeably arranged for either a right or left hand glove and when in an assembled position are securely held against 10 movement upon the body portion. This is effected by the contact between the end of the finger shank and the base of the kerf in connection with the cross pin which prevents longitudinal movement thereof. If it 15 be desired to remove a tightly fitting glove without turning the finger thereof, the hand portion is turned back so that the securing pin may be removed and the finger members withdrawn from the form with the glove 20 and subsequently removed separately therefrom. In fitting a glove upon the form the thumb member may be omitted until the fingers have been properly adjusted and then inserted in position to receive the glove 25 thumb. It will also be seen that the formation of the base of the digital members protects the shank sockets from moisture due to the presence of a wet glove upon the form.

30 The invention presents a simple, efficient and economically manufactured glove form adapted to receive and dry the wash gloves in general use, or to support a glove thereon for dry cleaning or other purposes.

35 What I claim is:—

1. A glove form comprising a body portion having a series of sockets at its upper edge and thumb sockets at its opposite side edges, digital members having shanks to 40 enter said sockets and formed with means at their inner ends to prevent lateral movement therein, and removable means engaging said sockets and members for retaining the same in position.

45 2. A glove form comprising a body portion having a series of sockets at its upper edge and thumb sockets at its opposite side edges, digital members having shanks engaging at their inner ends against the base 50 of said sockets, and a removable cross pin extending through said sockets at the upper edge of the body and the over-lapping portion of said shanks.

55 3. A glove form comprising a body portion having a series of sockets at its upper edge, interchangeable digital members having angular shanks to seat in contact with the lower portion of said sockets to prevent movement of said digital members, and a

removable securing pin engaging said shanks 60 and sockets.

4. A glove form comprising a body portion having a series of transverse slots at its upper edge, interchangeable digital members having shanks to enter said slots and provided with a flat face to engage the base thereof, a body at the base of said members extending beyond said shanks to cover the upper end of said slots, and means for detachably securing the shanks against movement in said slots.

5. A glove form comprising a body portion having a series of sockets at its upper edge and thumb sockets at its opposite side edges, interchangeable digital members secured against movement in said sockets, and a removable thumb member adapted to be secured in either thumb socket of the body portion to lie in the vertical plane of the digital members.

6. A glove form comprising a body portion having a series of transverse slots at its upper edge and diagonally disposed slots at the opposite sides edges thereof, finger members having shanks provided at their inner 85 ends with means to prevent pivotal movement therein, a pin extending through said shanks and slots to retain said members against longitudinal removal therefrom, and a thumb member having a shank removably 90 retained in one of said diagonal slots.

7. A glove form comprising a body portion having a series of transverse slots at its upper edge and diagonally disposed slots at the opposite side edges thereof, finger members having shanks parallel with the base of 95 said slots and a body covering the upper end thereof, a pin extending through said shanks and slots to retain said member against removal therefrom, a thumb member having a shank disposed in one of said diagonal slots, and a removable pin passing through said thumb shank to retain it in position.

8. A glove form comprising a body portion having a series of sockets at its upper 105 edge, and digital members having shanks to enter said sockets and formed to engage the base thereof to prevent lateral oscillation of said members.

9. A glove form comprising a body portion having a series of transverse slots at its upper edge with their base at an angle to the side walls thereof, and digital members having shanks to enter said slots and formed with a straight lower face to engage said 115 base.

In testimony whereof I affix my signature.
MARGARET T. KEARNS.
